CLARENCE HENRY GEIGER AND THOMAS E. DUNWODY, OF PRESSMEN'S HOME,
TENNESSEE.

METHOD OF AND MEANS FOR DAMPENING PLATE-CYLINDERS IN OFFSET-PROCESS PRINTING-PRESSES.

1,377,769.

Specification of Letters Patent. Patented May 10, 1921.

Application filed July 6, 1920. Serial No. 394,386.

To all whom it may concern:

Be it known that we, CLARENCE HENRY GEIGER and THOMAS E. DUNWODY, citizens of the United States, residing in Pressmen's 5 Home, in the county of Hawkins and State of Tennessee, have invented certain new and useful Improvements in the Method of and Means for Dampening Plate-Cylinders in Offset-Process Printing-Presses, of which 0 the following is a specification.

The principal object of our invention is to provide a simple and efficient method of dampening the plate cylinder of offset process printing presses without using separate 15 rollers for this purpose. Where separate dampening rollers are employed, as at present, the plate cylinder is quickly worn down by them, necessitating its frequent replacement. This involves labor and expense 20 which our method eliminates by uniformly distributing the water on the plate roller in the form of a spray.

Under our method of dampening the plate cylinder, it is possible to quickly and easily 25 increase the amount of water needed at certain places thereon. For instance, where the ink is heavier at one or more points on the surface of the plate cylinder than at others, the additional water required at those points 30 can be easily and efficiently supplied without the use of a sponge for this purpose.

It is another object of our invention to provide a method of dampening the plate cylinder that is clean and labor-saving, for 35 under our method there are no dampening rollers to be removed and cleaned. Under present conditions this is necessary when, after using ink of one color, it is desired to use ink of another color. Under our 40 method of dampening the plate cylinder, it is not necessary to stop for change of color.

It is a further object of our invention to provide simple and efficient means for 45 carrying the above method into effect.

Other important and incidental objects will be brought out in the following specification, and particularly set forth in the subjoined claims.

50 In the accompanying drawings, Figure 1 is a perspective view of an offset printing press equipped with our improved means for dampening the plate cylinder. Fig. 2 is

a cross section taken through the vaporizing means. Fig. 3 is a side view of the means 55 employed to impart a reciprocating movement to the vaporizing means. Fig. 4 is an end view of the actuating cam. And Fig. 5 is a view of the periphery thereof, showing the curved groove in it. 60

Throughout the specification and drawings, similar reference characters denote corresponding parts.

Referring to the accompanying drawings, the numeral 1 designates an offset process 65 printing press containing the usual plate cylinder roller 2. Supported by brackets 3, 3 behind the roller 2 is a tapering hood 4 open at both front and rear.

Laterally movable behind the hood 4, 70 along a transverse rod 5 supported by the brackets 3, 3, is a cylindrical water tank 6 which supports above it, by means of side plates 7, 7, a cylindrical chamber 8 adapted to receive compressed air through an inlet 75 tube 9. (See Figs. 1 and 2.)

Projecting upwardly from the water tank 6 is a series of vertical tubes 10, each of which terminates in a right-angled outlet portion within a nozzle 11. At its rear end 80 the latter is connected to the lateral portion 12 of a valve housing 13 into which projects a needle valve 14 operated by a handle 15. Each valve housing 13 is connected to the upper portion of the compressed air tank 85 8 from which the air, under pressure, is permitted to issue by screwing the needle valve 14 above its seat 16. The air that passes the needle valve 14 rushes into the nozzle 11, drawing therein through the tube 90 10, water from the tank 6. This water, in the form of a spray, issues from the ends of the nozzles 11, into and through the hood 4, to come in contact with the plate cylinder 2 for the purpose of dampening it. In 95 order that this water may be uniformly sprayed upon said cylinder the following means are provided.

Referring to Figs. 1, 3, 4 and 5, there is pivotally secured upon a fulcrum arm 100 17 projecting outwardly from a bracket 3, a rocker member 18 whose lower end terminates in a sector shaped cam portion 19. The member 18 is reciprocated by a connecting rod 20 pivotally secured at its 105 front end to the end face of the plate roller

2, whereby, when the latter is rotated, the cam 19 will be rocked for the following purpose.

Provided in the circular periphery of the cam 19 is a groove 21 adapted to receive a roller 22 carried by the outer end of an arm 23 secured to the adjacent end plate 7. The groove 21 is so curved that when the cam 19 is rocked, the latter will impart a back and forth movement to the spraying nozzle unit along the rod 5, to uniformly spray the water vapor issuing from the nozzles 11 upon the plate roller 2. While we have shown this form of means for moving the spraying nozzle unit back and forth along the rod 5, any other suitable means may be employed for this purpose without departing from the spirit of the invention. The spraying unit may be easily disconnected from the cam mechanism, and moved along the rod 5 to, and held in, a position to direct the vapor upon any particular place upon the plate roller 2 where the character of the ink requires an unusually large amount of water.

It is thus seen that our method of dampening the plate cylinder contemplates the spraying of the water upon it instead of dampening it by separate rollers. The latter rollers, when used, tend to wear down the plate, necessitating its frequent removal and replacement. The expense incident to the latter is eliminated by our method of dampening the plate cylinder by a spraying device which needs no dampening rollers to make its operation efficient. While we have shown and described a particular

form of spraying device for carrying our method of dampening the plate cylinder into effect, any other suitable device may be employed for this purpose without departing from the spirit of the invention.

Having described our invention, we claim:

1. The herein described method of dampening the plate cylinder of an offset process printing press, which consists in spraying upon the cylinder, water that is atomized by physical means that are given a back and forth movement along said cylinder.

2. In a device of the type described, the combination with a plate cylinder, of laterally movable nozzle means adjacent said cylinder to project water upon it for dampening purposes.

3. In a device of the type described, the combination with a plate cylinder, a laterally movable spraying device adjacent to said cylinder, and means connected to the plate cylinder for imparting a back and forth movement to the spraying device when the cylinder is rotated.

4. In a device of the type described, the combination with a plate cylinder, a laterally movable spraying device adjacent to said cylinder, and a cam operated by the plate cylinder for imparting a back and forth movement to the spraying device when the cylinder is rotated.

In witness whereof we have hereunto set our hands this 22nd day of June, 1920.

CLARENCE HENRY GEIGER.

THOMAS E. DUNWODY.

Witness:

Jos. C. ORR.
